UNITED STATES PATENT OFFICE

2,493,677

TANK AND SPRAY GUN

Anders Rudolf Lofstrand, Jr., Silver Spring, Md.

Application July 10, 1946, Serial No. 682,625

2 Claims. (Cl. 222—402)

1

This invention relates to portable sprayers.

An object of this invention is to provide an improved sprayer including a portable tank, a pump for placing the material under pressure, and a spray gun connected to the tank by a flexible hose.

Another object of this invention is to provide an improved insecticide tank which includes a strainer for straining the material as it is poured into the tank, and a pressure pump extending into the tank for placing the material under the desired pressure.

A further object of this invention is to provide in a sprayer an improved gun-type valve connected to the spray nozzle which will facilitate directing the material to the desired location.

With the above and other objects in view, my invention consists in the arrangement, combination and details of construction disclosed in the drawings and specification, and then more particularly pointed out in the appended claims.

In the drawings, wherein similar reference characters designate similar parts throughout the respective views,

Figure 1 is a detail top plan of a sprayer assembly constructed according to an embodiment of this invention.

Figure 2 is a detail side elevation, partly broken away and in vertical section, of the sprayer tank.

Figure 3 is a longitudinal section, partly broken away and in detail, of the spray gun or valve structure.

Figure 4 is a fragmentary side elevation of the tank opposite from that shown in Figure 2.

Referring to the drawings, the numeral 10 designates generally a tank structure which is formed of a cylindrical side wall 11, a top wall 12 which is upwardly bowed and formed with a marginal upturned flange 13 which may be welded or otherwise firmly secured to the side wall 11. Preferably the side wall 11 is formed with an annular inwardly projecting bead 14 which forms a seat or stop against which the top wall 13 is adapted to bear. The side wall 11 extends beyond the flange 13 of the top wall and the extension of the side wall 11 is reinforced by a reinforcing band 15 which may be welded or otherwise firmly secured to the extended side wall.

A reinforcing lower band 16 is also secured to the lower end of the side wall, which as shown in Figure 2, is formed with a lower annular inwardly projecting bead 17 against which the bottom wall is adapted to engage. The bottom wall is similar to the top wall.

The top wall 12 has mounted thereon a cylindrical filler member 18 which may be welded or

2

otherwise firmly secured to an inwardly turned annular flange 19 formed in the top wall 12. The nipple 18 has threaded on the upper end thereof a cap 20 which is formed with a pair of upwardly extending lugs 21. The cap 20 on the inner side thereof is formed with an inwardly projecting seat 22 against which a plate 23 is adapted to engage.

The plate 23 on its inner side has secured thereto a gasket 24 which is secured to the plate 23 by a fastening member 25. The plate 23 also includes an outwardly extending stud 26 which extends through the cap 20 and may be secured by means of a cotter pin 27 or other suitable fastening means. The cap 20 is preferably chained to the nipple 18 by means of an anchoring chain 28 which is fixed at one end to the nipple 18, and at the other end to a washer 29 interposed between the fastening member 25 and the gasket 24. The inner end of the nipple 23 has dependingly secured thereto a strainer 30.

The strainer 30 at its upper end is formed with a flange 31 engaging in the annular groove 32 formed in the nipple 18, and a split locking ring 33 is adapted to removably lock the strainer 30 in the nipple 18.

In order to provide a means whereby the insecticide within the tank 10 may be placed under air pressure, I have provided an air pump generally designated as 34. The pump 34 includes a cylinder 35 which is disposed in depending relation within the tank 10. The upper end of the cylinder 35 is formed with an annular flange 36 which engages against an annular flange 37 carried by a nipple 38. The nipple 38 is threaded into a sleeve 39 which is fixedly secured through the top wall 12, and a closure plate 40 bears against the upper side of the flange 36 of the cylinder 35, being secured thereto by means of fastening members 41. The cylinder 35 has fixed to the inner end thereof an end wall or cap 42 which is formed with a centrally disposed boss 43. The boss 43 has threaded thereinto a nipple 44 forming part of a check valve housing, and the nipple 44 has threaded on the inner end thereof a cap formed of a cylindrical member 45 and an end wall 46.

The cylindrical side wall 45 of the check valve cap generally designated as 47 is formed with one or more openings 48, and the end wall 46 is also formed with a central opening 49. A check valve plug 50 is adapted to normally engage against the inner or lower end of the nipple 44 which constitutes a valve seat, and a plug 50 is constantly urged to closed position by means of a spring 51. A piston generally designated as 52 is slidably mounted within the cylinder 35.

The piston 52 includes a cup-shaped washer 53 which is secured by means of a clamping ring or nut 54 to the lower end of a tubular piston rod 55. Preferably a coupling member 56 is threaded onto the lower end of a plug 57 which is fixed in any suitable manner in the lower end of the tubular piston rod 55. The plug 57 is formed with a bore 58 closed by means of a threaded plug 59. Air is admitted to the cylinder 35 above the piston 52 by means of an upper air opening 60 in the tubular rod 55, and a lower opening 61 also formed in the tubular rod. Upon upward pull of the rod 55 and the piston 52, air will slip past the gasket 53 and upon downward movement of the piston the gasket 53 will slidingly and sealingly engage the cylinder 35.

The piston rod 55 has fixed to the upper end thereof a stirrup shaped handle 62 formed with a boss 63 which is fixed about the upper end of the rod 55 by means of a pin 64. The handle 62 is formed with an opening 65 within which a spare spray nozzle 66 is locked by means of a screw or locking bolt 67. The top wall of the tank has extending therefrom an outlet hose 68 which is connected to the top wall 12 by means of a coupling 69, and the hose 68 is connected to a piston type valve structure and spray nozzle handle as shown in Figure 3.

The handle and valve structure include a handle member 70 formed with a bore 71. A coupling 72 is threaded into the lower end of the handle 70 and is formed with a nipple 73 on which a coupling member 74 is threaded for securing the outer end of the hose 68 to the handle. A tubular strainer 75 is carried by the coupling member 72 extending through the bore of this coupling member and into the bore 71 of the handle 70.

The handle 70 is also formed with a counterbore 76 communicating with a valve chamber 77 which is formed in an angularly disposed valve body or housing generally designated as 78. The body 78 is formed with a horizontally disposed chamber 79 communicating with the chamber 77 through a reduced diameter chamber 80. The reduced diameter chamber 80 forms a shoulder 81 against which a valve gasket 82 is adapted to engage.

A spherical valve plug 83 is loosely disposed in the chamber 77 and is adapted to be normally urged to closed position by means of a spring 84 carried by a hollow plug 85 which is threaded into the body 78. The inner end of the spring 84 bears against a plate 86 having a concave inner surface forming a ball seat for holding the plate 86 against lateral movement relative to the ball 83. The ball 83 is adapted to be moved to open position by means of an elongated rod 87 which is slidable in a bushing 88 threaded into the forward end of the bore or chamber 79. The rod 87 has a reduced diameter outer portion 89 forming a shoulder 90 which is adapted to abut against the inner end of the bushing 88 to limit the outward movement of the valve operating rod.

An annular flange 91 is also formed on the rod 87 and is adapted to engage against the inner end of the chamber or bore 79 in the event the rod 87 is moved inwardly to the limit of the movement provided for this rod. The rod 87 is also formed with a valve plug engaging the stem 92 which is of smaller diameter than the counterbore 80 so that the fluid can pass about the stem 92 when the valve 83 is in its open position.

tion. A cup-shaped knob 93 is fixed on the outer end of the rod 87 and is adapted to telescope over an extension 94 carried by the bushing 88.

The chamber or bore 79 has communicating therewith an upwardly and rearwardly inclined duct 95 which is formed in the body 78, and the duct 95 communicates at its upper or rear end with a horizontally disposed outlet chamber or duct 96. The body 78 is formed with an upwardly projecting lug 97 and with a cylindrical extension 98. A button locking lug 99 is carried by a sleeve 100 which is rotatable on extension 98 and is adapted, when in released position, to be in alignment with lug 97.

When the locking lug 99 is in locked position, it is swung downwardly to the dotted line position shown in Figure 3.

An elongated pipe 101 is connected to the extension 98 by means of a coupling 102, and a spray nozzle 103 is carried by the outer end of the pipe 101. The spray handle and the nozzle 103 are adapted to be releasably secured to the tank 10 by inserting the nozzle 103 into a socket 104 which is fixed to the side wall 11 of the tank 10 adjacent the lower end thereof. A U-shaped keeper 105, having outwardly directed flanges 106 is fixed to the upper end portion of the tank in alignment with the socket 104 so that when the spray structure is not in use, the spray gun 101 will be secured directly to the tank and the latter may be carried by means of the handle 62.

As shown in Figure 1, the handle 62 may be locked in its innermost position by means of oppositely directed lugs 107 which are carried by the closure plate 40. The boss 63 has oppositely extending pins 108 which are adapted to engage the lugs or keepers 107. The top wall 12 of the tank is also provided with a pressure gauge 109 of conventional construction so that the user of this device will be able to determine the working air pressure within the tank.

The tank 10, adjacent the bottom thereof, has extending laterally therefrom a foot or pedal member 110 of looped construction having an upwardly directed inner end 111 engaging an open barrel 112 which is fixed to the lower end of the tank. In this manner the tank 10 may be steadied by placing a foot on the foot member 110 during the pumping of air into the tank. In order to provide for carrying of the tank on the shoulder during the use of the device, I have provided a flexible strap 113 which is formed at the opposite ends thereof with snap hooks 114, 115 engageable with eyes 116, 117 respectively, which are loosely secured to the lower and upper portions of the tank 10.

In the use and operation of this tank, the tank 10 is filled with the desired insecticide by removing the cap 20 and discharging the insecticide through the strainer or filler 38. Preferably the tank is not filled to the top so that a substantial amount of air may be pumped into the tank by operation of the pump 34. When the desired amount of pressure is in the tank 10, the spray handle 78 may be held in one hand and the pipe 101 directed to the desired point. Inward pressure on the button or knob 93 will move the ball valve 83 to open position so that the insecticide may flow through the bore 71 of the handle 70 and pass the valve 83 into the chamber 79. From the chamber 79, the insecticide will flow through duct 95 into the outlet duct 96 and then pass the spray nozzle 103. If it is desired to lock the knob 93 in valve opening position, the locking lug 99 is

swung downward to the dotted line position shown in Figure 3.

I do not mean to confine myself to the exact details of construction herein disclosed, but claim all variations falling within the purview of the appended claims.

Having thus described my invention, what I desire to claim is:

1. In a sprayer tank, an air pump projecting partly into said tank, said pump comprising a cylinder formed with an upper flange, an internally threaded sleeve fixed in the top wall of said tank, a nipple threaded into said sleeve, a flange carried by the upper end of said nipple, said cylinder flange seating on said nipple flange, a closure plate engaging on said cylinder flange, means securing said closure plate, and said cylinder and nipple flanges together for dependingly mounting said cylinder in said tank, an inner end wall carried by said cylinder, an inwardly opening spring-pressed check valve carried by said inner end wall, a piston slidable in said cylinder, a tubular piston rod fixed to said piston slidable through said closure plate and having an upper intake opening, and a lower outlet opening, and a handle fixed on the upper end of said rod. 20

2. In a sprayer tank, an air pump projecting partly into said tank, said pump comprising a cylinder formed with an upper flange, an internally threaded sleeve fixed in the top wall of said tank, a nipple threaded into said sleeve, a flange carried by the upper end of said nipple, 25

5 10 15

said cylinder flange seating on said nipple flange, a closure plate engaging on said cylinder flange, means securing said closure plate, and said cylinder and nipple flanges together for dependingly mounting said cylinder in said tank, an inner end wall carried by said cylinder, an inwardly opening spring-pressed check valve carried by said inner end wall, a piston slidable in said cylinder, a tubular piston rod fixed to said piston slidable through said closure plate and having an upper intake opening, and a lower outlet opening, a handle fixed on the upper end of said rod, a pair of oppositely facing keepers carried by said closure plate, and a pair of locking lugs fixed to said handle and engageable with said keepers upon partial rotation of said handle to thereby lock said handle relative to said tank.

ANDERS RUDOLF LOFSTRAND, JR.
